CLAIM

The ornamental design for a vehicle wheel as shown and described.

DESCRIPTION

FIG. 1 is a front perspective view of a vehicle wheel illustrating our new design;

FIG. 2 is a rear perspective view thereof;

FIG. 3 is a front elevation view thereof;

FIG. 4 is a rear elevation view thereof; and,

FIG. 5 is a side elevation view thereof.

The broken lines in the drawings illustrate portions of the vehicle wheel that form no part of the claimed design. The dot-dashed lines are included for the purpose of illustrating boundary lines and form no part of the claimed design.
